US00D795823S

(12) **United States Design Patent** (10) Patent No.: **US D795,823 S**
 Aoyagi et al. (45) Date of Patent: **** Aug. 29, 2017**

(54) **COMPONENT FOR ELECTRONIC DEVICE**(71) Applicant: **Apple Inc.**, Cupertino, CA (US)(72) Inventors: **Shota Aoyagi**, San Francisco, CA (US); **Richard P. Howarth**, San Francisco, CA (US); **Shayan Malek**, San Jose, CA (US); **Scott A. Myers**, San Francisco, CA (US); **David A. Pakula**, San Francisco, CA (US); **Gregory Nicolaus Stephens**, Sunnyvale, CA (US)(73) Assignee: **Apple Inc.**, Cupertino, CA (US)(***) Term: **15 Years**(21) Appl. No.: **29/581,007**(22) Filed: **Oct. 14, 2016****Related U.S. Application Data**

(63) Continuation of application No. 29/501,054, filed on Aug. 29, 2014, now Pat. No. Des. 769,833.

Primary Examiner — Elizabeth J Oswecki(74) *Attorney, Agent, or Firm* — Sterne, Kessler, Goldstein & Fox P.L.L.C.**CLAIM**

The ornamental design for a component for electronic device, as shown.

DESCRIPTION

FIG. 1 is a front perspective view of a component for electronic device showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 7 Drawing Sheets(56)
